UNITED STATES PATENT OFFICE.

WILLIAM H. ADAMS, OF KENYON, RHODE ISLAND, ASSIGNOR TO EASTERN FINISHING WORKS, INC., OF KENYON, RHODE ISLAND, A CORPORATION OF RHODE ISLAND.

DESIGN FOR A PRINTED FABRIC.

Application filed February 3, 1927. Serial No. 20,594. Term of patent 7 years.

To all whom it may concern:

Be it known that I, WILLIAM H. ADAMS, a citizen of the United States, residing at Kenyon, in the county of Washington and State of Rhode Island, have invented a new, original, and ornamental Design for Printed Fabrics, of which the following is a specification, reference being had to the accompanying drawing, forming part thereof.

The figure is a view of the fabric having my new design printed thereon.

I claim:

The ornamental design for a printed fabric, as shown.

In testimony whereof, I have signed my name to this specification.

WILLIAM H. ADAMS.
